UNITED STATES PATENT OFFICE.

JAMES L. MCCLINTOCK, OF WICHITA, KANSAS.

ANTIRATTLING DEVICE.

Application filed August 5, 1918, Serial No. 248,325. Renewed April 14, 1922. Serial No. 552,599.

To all whom it may concern:

Be it known that I, JAMES L. MCCLINTOCK, a citizen of the United States, and resident of Wichita, in the county of Sedgwick and State of Kansas, have invented certain new and useful Improvements in an Antirattling Device, of which the following is a specification, reference being had thereto in to the accompanying drawings.

10 This invention relates to an anti-rattling device. It is especially designed for use as a connecting member between two bodies relatively movable so that while they may be freely moved without increased friction between their surfaces, rattling and jarring due to the space between the members will be eliminated.

15 More specifically, the invention comprises a device especially adapted for use in connection with windows, doors and the like so that rattling, the admission of air, dust, and the like in the spaces usually existing between the windows, will be eliminated or reduced to a minimum, and which will, at the same time, permit a free sliding of the parts, and the device itself be entirely hidden from view.

20 It is a still further object within the contemplation of the present invention to construct a device of this character which will be very easily manufactured, consist of few parts, and which may be easily applied.

25 Other objects and advantages will in part be apparent and in part be brought out more clearly in the description which follows.

30 A drawing illustrating an embodiment of the present invention is hereto attached, the following views being shown:—

35 Figure 1 is a view in side elevation illustrating an application of my invention in connection with two relatively movable members; and

40 Figs. 2 and 3 are detail views in perspective of parts of the apparatus.

45 Referring specifically to the drawing, 1 and 2 designate members such as a window and frame or the like, one of which has a sliding movement in relation to the other, and the surface of one bearing upon the 50 surface of the other during such movement. In the present instance, 1 would represent a permanent part of the structure, such for instance as the window frame, whereas 2 would represent the window. Adapted to be 55 associated with these members is the device which comprises my invention. It consists

of a plate or body portion 3 having upon one of its edges a cut away portion 4 bent back into approximately perpendicular arrangement with the plane of the surface of the 60 body portion 3 to constitute a lip. The body portion 3 is provided with openings 5 and 6, and the lip is provided with an opening 7. The openings 5 and 6 are adapted to receive screws or the like fastening means 8 65 for the purpose of securing the plate in position, and it is usually disposed in a countersunk portion such as 9, of the article to which it is to be attached. One of the screws 8 also constitutes a bearing and retaining means for a loop or the like 10 disposed on the end of a resilient arm 11 which carries at its other extremity an offset portion 12 which has an angular relation thereto, and a bearing carrying a rotatable bear- 70 ing member 13.

75 Means are provided for forcing the rotatably bearing member 13 into engagement with the surface of a member with which the device is to co-operate, and means are also provided for adjustably varying the tension between these members. As here shown, such means comprise a bolt or the like 14 threaded into the opening 7, and bearing against the arm 11 intermediate its 80 ends as shown particularly in Fig. 1. Means are provided for locking this bolt in various positions of adjustment, and as here shown, a nut or the like 15 is threaded upon the other end of the bolt.

90 When used in connection with a window or the like, the inner portion of a section of the frame may be bored out as by an auger at two spaced-apart locations and the material between these dug out in any suitable way. The device may be readily attached by inserting the screws 8 within the auger holes and driving them home. When so placed the device is usually covered up by a strip or the like of some suitable material 95 such as a portion of the frame work and creates a frictionless bearing between the bearing member 13 and the surface of the window and the like, and at the same time maintains a close fit and considerable outward pressure which may be varied according to the adjustment of the bolt 14.

100 From the foregoing it will be seen that the present invention provides a simple and effective means of producing the objects 110 herein set forth and while it has been disclosed in the embodiment herein illustrated,

it will be understood that many changes may be made in the general arrangement of the parts without departing from the spirit of the invention or its scope as set forth in the claims.

What I claim is:—

1. An anti rattling device adapted to be enclosed into a portion of a window and comprising a plate; a lip disposed on the plate 10 in angular relation to a face thereof and within the edges of the plate; said plate being provided with openings for the reception of securing means; a resilient arm, provided at one end with a loop adapted to 15 encircle and have a bearing on one of the

securing means; a bearing member on the opposite end of the arm; and a member disposed in the opening in the lip and bearing against the resilient arm, all of said members being within the confines of the edges 20 of the plate.

2. The structure set forth in claim 1 wherein the member disposed in the opening of the lip is a threaded adjusting member adapted to vary the tension on the resilient arm, and means for locking the member in various positions of adjustment. 25

In testimony whereof I hereto affix my signature.

J. L. McCLINTOCK.
